MOLD EJECTING MECHANISM FOR
MOLD-FORMING MACHINES

Emery I. Valyi, Bronx, N. Y.

Application June 20, 1951, Serial No. 232,505

7 Claims. (Cl. 22—48)

1

This invention relates generally to machines for producing foundry molds in shell form from a molding mixture comprising a refractory and a bonding agent.

In producing shell molds in machines of this character an excess quantity of the molding mixture is applied to the face of a preheated metal pattern which is mounted in a suitable pattern-carrier. The mixture is held in contact with the pattern until the contacting portion thereof bonds and solidifies into a partially cured layer or shell having a uniform thickness of, for example, between one-eighth inch and one-quarter inch. The thickness of the shell depends on the time of contact of the mixture and the temperature of the pattern. The unbonded portion of the mixture is then removed from the pattern leaving the partially cured shell thereon. The shell is then subjected to a curing temperature of, for example, between 500° F. and 900° F. until the shell is cured to a hard, rigid, strong condition. The mold is then stripped from the pattern after which the pattern is treated with a parting solution and the operation repeated. The advance 10 treating of the pattern with a parting solution prevents the shell from adhering to the pattern so tightly that it might be broken during stripping.

This application is specifically directed to the mechanism for stripping the cured shells from the patterns and removing the shells from the machine. The embodiment of the invention shown and described herein is especially adapted for use in the mold-forming machine disclosed in my co-pending application Serial No. 226,229, filed May 14, 1951. But by slightly modifying minor details of construction the mechanism may be equally well adapted for use in various other shell mold-forming machines.

As shown herein a metal pattern is mounted in a suitable pattern carrier secured between two spaced parallel conveyor chains by which the pattern carrier is advanced to and away from the stripping mechanism. The pattern carrier also carries an ejector plate which is slidably mounted on a plurality of rods which are secured to and extend downwardly from the underside of the pattern carrier. The ejector plate has secured thereto a plurality of stripping pins which extend upwardly through apertures in the pattern and terminate flush with the face of the pattern. The number and the arrangement of the stripping pins is dependent upon the shape of the pattern and the mold formed thereon. In stripping a mold shell from a pattern the ejector plate is engaged by suitable mechanism and moved toward the carrier which projects the stripping pins out through the apertures in the pattern, thus stripping the shell from the pattern.

As shown herein the pattern carrier and the

2

pattern, with a cured mold shell adhering to the face thereof, are presented to the stripping mechanism in inverted position between the ejector plate actuating mechanism and a mold-receiving tray which is removably secured in position on a reciprocal carriage. As the pattern-carrier advances into stripping position the ejector plate-actuating mechanism engages opposite sides of the ejector plate. The plate-actuating mechanism remains inactive until the receiving tray has been moved upwardly from its carriage into proximity with the mold shell, after which the ejector plate and the tray are moved downwardly in unison until the tray comes to rest on the carriage. The ejector plate is then returned to its original position while the tray with the mold shell thereon remains in its original position on the carriage. The carriage is then actuated by suitable mechanism to convey the tray and shell thereon out of the machine where the mold shell is removed from the tray. The carriage with the tray thereon is then returned to its original position, after which everything is in readiness for the next stripping operation.

The principal object of the invention is to provide in a shell mold-forming machine improved mechanism for stripping shell molds from patterns and conveying the shell molds from the machine.

Another object of the invention is to provide a mechanism of this character which is efficient in operation, is of relatively simple construction, and which is operative to successively strip mold shells from patterns presented thereto without danger of breaking the shells during stripping and discharge thereof from the machine.

Other and more limited objects of the invention will be apparent from the following specification and the accompanying drawings forming a part thereof wherein:

Fig. 1 is a fragmentary longitudinal section through a mold-forming machine showing my improved mold-stripping and discharge mechanism in side elevation, the plane of the section being indicated by the line 1—1 of Fig. 2;

Fig. 2 is a fragmentary transverse section through the mold-forming machine of Fig. 1 showing the stripping and discharge mechanism of Fig. 1 in end elevation, the plane of the section being indicated by the line 2—2 of Fig. 1;

Fig. 3 is a horizontal section taken on the line 3—3 of Fig. 1;

Fig. 4 is an enlarged vertical section taken on the line 4—4 of Fig. 2;

Fig. 5 is a view similar to Fig. 4 showing the mold-receiving tray raised from its carriage into engagement with a mold shell preparatory to stripping the shell from its pattern;

Fig. 6 is an enlarged vertical section taken on the line 6—6 of Fig. 2 showing the mold shell

stripped from the pattern onto the receiving tray with the various parts in the position they assume at the end of the stripping operation;

Fig. 7 is a fragmentary view similar to Fig. 6 showing the carriage conveying the tray and shell out of the machine;

Fig. 8 is an enlarged fragmentary horizontal section taken on the lines 8—8 of Figs. 2 and 9;

Fig. 9 is a vertical section taken on the line 9—9 of Fig. 8;

Fig. 10 is a detail section taken on the line 10—10 of Fig. 9; and

Fig. 11 is an enlarged detail section taken on the line 11—11 of Fig. 3.

Referring now to the drawings by reference characters, the numeral 1 indicates the frame of a mold-forming machine, such as that shown and described in my aforesaid co-pending application Serial No. 226,229, filed May 14, 1951. The mold-forming machine includes a pair of spaced parallel chains 2 which are arranged to be intermittently driven in the direction indicated by the arrows A around idler sprockets 3 which are rotatably mounted upon stub shaft 4 carried by the frame 1.

A pattern-carrier 5 is secured to and between the chains 2 for movement therewith. Each pattern-carrier 5 comprises a rectangular frame 14 having an inturned annular flange 15 around the lower edge thereof. A heavy thick metal pattern 16 is removably secured within the frame 14 upon the inturned flange 15 by any suitable means, not shown. The frame 15 has a pair of shaft hangers 17 formed integral therewith and extending downwardly therefrom, one at each side midway between the forward and rear ends thereof. A transverse shaft 18 is rigidly secured in bores 19 in the hubs 22 of the hangers 17 by pins 23. The shaft 18 is rotatably mounted in the hubs 24 of a pair of opposed trunnion links 25, one of which is interposed in each of the chains 2 in place of one of the standard chain links. A rocker arm 26 is keyed to each end of the shaft 18 adjacent the trunnion links 25. Each of the rocker arms 26 carries a pair of rollers 28, one at each end thereof, which are adapted to ride on tracks 29 which are mounted upon the frame 1 along the outside of each of the chains 2. Each end of the shaft 18 has an inwardly extending axial bore 32 therein in which is slidably mounted a rod 33 which carries a locking bar 34 at the inner end thereof. The locking bars 34 extend out through elongated slots 35 in the shaft 18 and into opposed slots 36 and 37 in the hanger hubs 22 and the trunnion-link hubs 24, respectively. As shown in Figs. 8 and 9, the depth (front to back) of the slots 36 in the hanger hubs 22 is at least equal to the width of the locking bars 34, and is substantially greater than the depths of the slots 37 in the link hubs 24, so that the locking bars 34 may be entirely withdrawn from the slots 37 into the slots 36, but cannot be entirely withdrawn from the slots 36 into the slots 37. Thus, when the locking bars 34 are disposed in both the slots 36 and 37 as shown in Figs. 8 and 9, the shaft 18 and the frame 14 carried thereby are locked against rotary movement with respect to the trunnion links 25; and when the locking bars 34 are withdrawn from the slots 37 into the slots 36, the shaft may be rotated in the trunnion links 25 by the rocker arms 26 to shift the frame 14 from upright to inverted position, or vice versa, as and for the purpose hereinafter described. The rods 33 carry small rods 38 adjacent the outer

ends thereof which extend out through elongated vertically aligned slots 42 and 43 in the shaft 18 and the rocker arms 26, respectively. A small roller 44 is mounted on each end of the rods 38. Springs 45 in the bores 32 behind the rods 33 urge the rods 33 outwardly and the locking bars 34 into locking position in the slots 37. The locking bars 34 are moved into the slots 36 out of locking position by moving the small rods 38 and through them the rods 33 inwardly against the outward pressure of the springs 45.

A plurality of rods 46 having heads 47 on the lower ends thereof are secured to the underside of the frame 14 and extend downwardly therefrom one at each corner thereof. An ejector plate 48 is slidably mounted upon the rods 46. In normal upright position of the pattern carrier 5 the plate 48 rests upon the heads 47 of the rods 46, and is yieldingly held thereagainst by balls 49, in horizontal bores 52 in the plate 48, which are urged into engagement with tapered notches 53 in the rods 46 by springs 54. Plates 55 carrying a plurality of stripping pins 56 are removably secured to the ejector plate 48. The stripping pins 56 extend upwardly from the plates 55 through bores 57 in the pattern 16 with the upper ends thereof normally terminating flush with the upper surface of the pattern 16. The ejector plate 48 has two spaced outwardly extending cylindrical bosses 58 secured to each side thereof which are adapted to be engaged by the plate-actuating mechanism to move the ejector plate toward the frame 14. The movement of the plate 48 projects the stripping pins 56 out through the bores 57 which strips the mold shell 59 from the pattern as is explained in detail hereinafter.

The stripping mechanism comprises the ejector plate-actuating mechanism which is disposed above the conveyor chains 2 and a mold-receiving tray 61 which is disposed below the chains 2. The tray 61 is removably secured in place on a discharge carriage 62 for movement therewith into and out of the molding machine.

The carriage 62 comprises a plate 63 which is secured to a pair of spaced parallel elongated racks 64 which are supported by pinion gears 65 at the forward ends thereof and by guides 66 spaced inwardly of the machine from the pinion gears 65. The pinion gears 65 are keyed to a shaft 67 which is rotatably mounted in suitable bearing blocks 68. The guides 66 and the bearing blocks 68 are rigidly secured to the molding machine frame 1. A pinion gear 69 having a much smaller pitch diameter than the gear 65 is keyed to the shaft 67 between the gears 65. The pitch diameter of the gear 69 is preferably about one-third of the pitch diameter of the gears 65, but this ratio is not essential and may be varied if desired. The pinion gear 69 meshes with a reciprocal rack 70 which is operatively connected to a hydraulic cylinder and piston assembly 71 for reciprocation thereby. The outward movement of the rack 70 rotates the shaft 67 and gears 65, through the gear 69. The rotation of the gears 65 moves the racks 64 and plate 63 carried thereby outwardly at approximately three times the speed of movement of the rack 70 due to the difference in the pitch diameter of the gears 65 and 69. By this arrangement the carriage 62 is moved a fixed distance by a much lesser movement of the rack 70. When the rack 70 is moved in the opposite direction the carriage 62 is brought back to its original position in the machine in the same manner. As the carriage 62 is moved outwardly from the machine the racks

64 engage supporting guides 72 secured to the frame 1.

The tray 61 comprises a rectangular frame 75 and a mold support 76 which conforms to the contour of the pattern and mold shell and is removably secured in the frame 75. It will be understood that when a different pattern 16 is used a correspondingly different mold support 76 will be used. The frame 75 has a plurality of transversely extending angle irons 77 secured to the underside thereof which seat upon the plate 63 of the carriage 62. Certain of the angle irons 77 have blocks 78 rigidly secured to the sides thereof. The blocks 78 have vertical apertures 79 therein into which pins 80 secured to the plate 63 extend when the tray 61 is in place on the carriage 62. It will be apparent that with this construction the tray 61 may be raised vertically from the carriage 62, but cannot be shifted laterally thereon. The frame 75 has a longitudinally extending channel member 81 secured to each side thereof.

The ejector plate-actuating mechanism 86 is mounted upon a platform 85 carried by the frame 1 above the conveyor chains 2 and comprises a vertically reciprocal beam 86 which is adapted to be raised and lowered by a hydraulic cylinder and piston assembly 87 which is carried by the platform 85 and is operatively connected to the beam 86 at the geometrical center thereof. Two pairs of rods 88 are rigidly secured to the beam 86, one pair adjacent each side thereof, and extend downwardly therefrom through guide sleeves 89 carried by the platform 85. Each pair of rods 88 has an inwardly extending bracket 90 adjustably secured to the lower ends thereof. When the carriage 62, with tray 61 thereon, is in its normal position within the machine the inner edges of the brackets 90 are disposed in the grooves in the channel members 81 secured to the sides of the tray frame 75. With this construction it will be apparent that as the beam 86 is raised and lowered by the cylinder and piston assembly 87 the tray 61 will be raised and lowered in unison therewith.

Two pairs of rods 91 are slidably mounted for vertical reciprocation in guide sleeves 92 carried by the platform 85 and vertically aligned sleeves 93 carried by the beam 86. A bar 94 having a longitudinally extending groove 95 in the inner face thereof is rigidly secured to the lower ends of each pair of rods. Pneumatic cylinder and piston assemblies 96 which are secured to the underside of the platform 85 and extend downwardly therefrom are operatively connected to the bars 94, one assembly 96 being connected to each bar 94. The cylinder and piston assemblies 96 constantly bias the bars 94 and the rods 91 connected thereto to their uppermost position. Latching means 100 is provided adjacent each pair of rods 91 by which the rods 91 are locked to the beam 86 for downward movement therewith. As a pattern-carrier 5 is moved into stripping position by the conveyor chains 2 and bosses 58 secured to and extending outwardly from each side of the ejector plate 48 enter the grooves 95 in the bars 94. Then, as the bars 94 are raised and lowered, the ejector plate 48 is raised and lowered in unison therewith.

Each latching means 100 comprises a pair of opposed arms 101 which are pivotally mounted on brackets 102 which are secured to and extend downwardly from the underside of the beam 86 beside each of the rods 91. The arms 101 are biased outwardly from each other by a spring 75

103 which is connected to and between the arms 101 slightly above a plane through the pivoted axis of the arms. The outward movement of the arms 101, under the influence of the spring 103, is limited by adjustable stops 104, mounted in lugs 105 on the brackets 102, which are engaged by fingers 106 extending upwardly from the arms 101. Each arm 101 has a notch 107 near the lower end thereof which is adapted to engage a roller 108 carried by the associated rod 91. Each arm 101 also carries a roller 109 at the lower end thereof which is adapted to engage a stationary cam 110, mounted on the platform 85, as the beam 86 approaches the lower limit of its movement.

In operation a pattern-carrier 5 with a cured shell mold 59 adhering to the pattern 16 carried thereby, is presented to the stripping and discharge mechanism in inverted position as shown in Fig. 4, with the bosses 58 on the sides of the ejector plate 48 engaging in the notches 95 of the bars 94. Pressure is then applied to the underside of the piston of the cylinder and piston assembly 87 which raises the beam 86 from the position shown in Fig. 4 to the position shown in Fig. 5. As the beam 86 moves upwardly it raises the tray 61 from the carriage 62 up into engagement with the mold shell 59. During the upward movement of the beam 86 and tray 61 the bars 94 remain stationary in their uppermost position, being held there by the pneumatic pressure in the cylinder and piston assemblies 96. At the upper limit of movement of the beam 86 the arms 101 are swung outwardly by the spring 103 until the notches 107 engage the rollers 108 carried by the rods 91 which locks the bars 94 to the beam 86 for downward movement therewith. Pressure is then applied to the upper side of the piston of the cylinder and piston assembly 87 to move the beam 86 downwardly against the constantly exerted upward pressure of the cylinder and piston assemblies 96. As the beam 86 is moved downwardly from the position shown in Fig. 5 to the position shown in Fig. 6, the tray 61, the bars 94, the ejector plate 48 and the stripping pins 56 are all moved downwardly by the beam 86 in unison therewith. As the beam 86 approaches the lower limit of its movement, the roller 109 on the arms 101 engage the cams 110 which cam the arms 101 inwardly out of engagement with the rollers 108 carried by the rods 91 thus freeing the rods 91 and bars 94 from the beam 86. The cylinder and piston assemblies 96 then return the rods 91, bars 94, ejector plate 48, and stripping pins 56 back to their original position as shown in Figs. 4, 5 and 7, and the beam 86, rods 91 and brackets 90 remain in their lowermost positions with the tray 61, with the mold shell 59 thereon, in position on the carriage 62 and the brackets 90 engaging in the slots in the channel members 81 on the tray frame 75. The mechanism is now in the position shown in Figs. 2 and 4 ready for the carriage 62 to convey the stripped mold shell 59 from the machine. Pressure is then applied to the cylinder and piston assembly 71 which actuates the carriage as shown in Figs. 3 and 7 to convey the tray 61 with the mold shell 59 thereon out of the machine. As the tray 61 is moved outwardly by the conveyor the channel members 81 slide out of engagement with the brackets 90. After the mold shell 59 has been removed from the tray the pressure in the cylinder and piston assembly 71 is reversed which returns the carriage and tray back to their original position in

the machine with the channel members 81 again engaging the brackets 90.

The mechanism is now in condition for the next stripping operation. After the mold shell 59 has been stripped from the pattern 16 onto the tray 61 and the ejector plate 48 and the stripping pins 56 have been returned to their normal position, the pattern-carrier is moved away from stripping position and returned to upright position in readiness for the forming of another mold shell.

From the foregoing it will be apparent to those skilled in this art that I have provided a very simple and efficient mechanism for stripping mold shells from the patterns on which they are formed and discharging them from the mold-forming machine.

It is to be understood that I am not limited to the specific construction shown and described herein as various modifications may be made therein within the scope of the appended claims.

What is claimed is:

1. A mechanism for stripping mold shells from patterns comprising a pattern-carrier having a pattern mounted thereon, an ejector plate slidably supported by said pattern-carrier in spaced relation thereto, a plurality of stripping pins secured to said ejector plate and extending into apertures in said pattern and terminating flush with the face of said pattern, vertically movable mold-receiving means below said pattern carrier, a reciprocal beam and means by which said beam is reciprocated, interconnecting means between said beam and said mold-receiving means through which said mold-receiving means is moved vertically toward and away from said pattern-carrier by the reciprocation of said beam, ejector plate-gripping mechanism, releasable latching means between said beam and said ejector plate-gripping mechanism through which said gripping-mechanism is actuated by said beam to move said ejector plate in unison with said receiving means in a direction to project said stripping pins out through said apertures beyond the face of said pattern for stripping a mold shell from said pattern onto said mold-receiving means while maintaining said mold receiving means in mold supporting position during the stripping thereof from said pattern.

2. A mechanism for stripping mold shells from patterns comprising a pattern-carrier having a pattern mounted thereon, an ejector plate slidably supported by said pattern-carrier in spaced relation thereto, a plurality of stripping pins secured to said ejector plate and extending into apertures in said pattern and terminating flush with the face of said pattern, vertically movable mold-receiving means mounted below said pattern, a platform disposed above said mold-receiving means, a plurality of rods slidably mounted in guides carried by said platform, a beam rigidly secured to the upper ends of said rods, a pair of spaced opposed brackets rigidly secured to the lower ends of said rods, means slidably connecting said mold-receiving means to and between said brackets, means operative to move said pattern-carrier into stripping position between said mold-receiving means and said platform, a second set of rods slidably mounted in aligned guides carried by said platform and said beam, a pair of spaced opposed ejector plate-gripping means rigidly secured to the lower ends of said second mentioned rods, means yield-

ably holding said ejector plate-gripping means and the rods secured thereto in their normal up position, means operative to raise and lower said beam to move said mold-receiving means into and out of mold-receiving position, and releasable latching means operative to lock said second set of rods to said means for downward movement therewith, whereby said mold-receiving means, said ejector plate and said stripping pins are all moved downwardly in unison thereby stripping a mold shell from said pattern onto said mold-receiving means.

3. A mechanism for stripping mold shells from patterns, as set forth in claim 2, having means operative to move said mold-receiving means into and out of engagement with said brackets.

4. A mechanism for stripping shell molds from patterns, as set forth in claim 2, in which said releasable latching means comprises a plurality of pivoted arms carried by said beam, engageable means carried by each of said second set of rods, means operative to move said arms into engagement with said engageable means as said beam approaches the upper limit of its movement, and means operative to move said arms out of engagement with said engageable means as said beam approaches the lower limit of its movement.

5. A mechanism for stripping mold shells from patterns, as set forth in claim 4, having means operative to move said mold-receiving means into and out of engagement with said brackets.

6. A mechanism for stripping mold shells from patterns, as set forth in claim 1, in which said releasable latching mechanism comprises a plurality of pivoted arms, engageable means carried by said ejector plate-gripping mechanism, means operative to move said arms into engagement with said engageable means as said beam approaches the limit of its movement in one direction, and means operative to move said arms out of engagement with said engageable means as said beam approaches the limit of its movement in the other direction.

7. A mechanism for stripping mold shells from patterns comprising a pattern-carrier having a pattern mounted thereon, an ejector plate slidably supported by said pattern-carrier in spaced relation thereto, a plurality of stripping pins secured to said ejector plate and extending into apertures in said pattern, a vertically movable mold receiving means below said pattern holder, means operative to move said mold-receiving means upwardly substantially into contact with said mold shell on said pattern, and means operative to move said mold-receiving means and said ejector plate downwardly in unison in a direction to project said stripping pins out through said apertures beyond the face of said pattern for stripping a mold shell from said pattern onto said mold-receiving means while maintaining said mold receiving means in supporting relationship to said mold shell.

EMERY I. VALYI.
